UNITED STATES PATENT OFFICE

ERNEST W. NAYLOR, OF NEW YORK, N. Y.

PUNCHING AND FLANGING MACHINE.

SPECIFICATION forming part of Letters Patent No. 440,051, dated November 4, 1890.

Application filed June 11, 1889. Serial No. 313,950. (No model.)

To all whom it may concern:

Be it known that I, ERNEST W. NAYLOR, a citizen of the United States, and a resident of the city, county, and State of New York, have 5 invented certain new and useful Improvements in Punching and Flanging Machines; and I do hereby declare that the following is a full, clear, and exact description of the invention, such as will enable others skilled in 10 the art to which it appertains to make and use the same, reference being had to the accompanying drawings, in which—

Figure 1 represents a side elevation of my 15 improved machine, the dies and clamping-head being shown in section in their depressed position. Fig. 2 is a top plan of the entire machine. Figs. 3 and 4 show, respectively, side elevation and top plan of the machine when used for flanging sheets of large dimensions. Fig. 5 represents a vertical section on the line $x-x$ of Fig. 1, showing the female die raised and the manner of connecting the clamping-head and female die to their respective rams. Fig. 6 is a plan of the platen to 25 which the female die is attached. Fig. 7 is a similar detached view of the female die. Fig. 8 is a section on the line $y-y$ of Fig. 6. Fig. 9 is a top plan of the clamping-head, showing the points of attachment of the clamping-plungers. Figs. 10 and 11 show the manner 30 of attaching the punches to the plungers when the machine is used for punching, and Figs. 12 and 13 represent detail views of the die-guide shown in Figs. 3 and 4.

35 My invention relates to that style of punching and flanging machine adapted to be operated by hydraulic rams or plungers. Its object is to provide a machine of the character described which may be used either for punching or flanging, or for both punching and flanging; also, to provide a machine adapted for operating on either large or small plates.

40 To these ends my invention consists of one or more vertical rams for clamping the work to the anvil, and two or more vertical rams for operating the movable die, and also in a horizontal ram carrying a die or punch for finishing the turned-down edge.

45 It also consists in hinged standards at one end of the machine adapted to assume a horizontal position to permit of the insertion of very large sheets of metal; also, in minor de-

tails of construction and combinations of parts, which will be hereinafter more fully described, and distinctly pointed out in the specification and claims.

55 In the drawings, A represents the upper and A' the lower girders of the frame, which are supported and held apart by means of four standards or pillars G G and G' G', the former of which are hinged at $e-e$ to the lower girder A' and adapted to be disconnected from the upper girder, as will hereinafter more fully appear.

60 In order to strengthen the frame when the machine is operating on very large material the upper and lower girders A A' are connected by an intermediate brace A² at the end having the rigid standards. In the upper girder A are mounted three or more hydraulic cylinders C B C, placed side by side in a vertical position. In the present machine I have shown two rows of such cylinders, and on the lower girder is suitably mounted an anvil-block H, upon which the metal to be operated on is clamped by a clamping-head I, carried at the ends of the plungers B' B' of the cylinders B B. To the ends of the plungers C' C' C' C' of cylinders C C C C, located on opposite sides of the cylinders B B is secured 70 a platen J, to which the female die K is secured, suitable openings j being formed in said platen for the passage of the plungers B' B', carrying the clamping-head I. The clamping-head and die platen are secured to 75 their respective plungers by means of countersunk bolts g.

80 In order to adapt the machine for operating upon material of large dimensions I hinge the standards G G to the lower girder at the points $e-e$, the upper or free ends of said standards being connected by a rigid cross-head L, the upper girder A being provided with open slots or notches a' for the reception of the standards or pillars G G, the standards being 85 screw-threaded above the girders for the reception of clamping-nuts g', by which the standards are held in place in the upper girder.

90 On the standards G G is a sliding cross-head M, which is capable of adjustment thereon by means of a screw F, journaled in the rigid cross-head L and having collars ll to prevent 95 longitudinal movement of the screw. A block 100

N, carrying a centering-pin *a*, is mounted in a guideway in the adjustable cross-head M, and is laterally adjustable therein by means of a screw E, secured at its ends in said cross-head. In order to finish the flange either by corrugating or punching I provide a hydraulic ram D on the lower girder, the plunger of which carries at its end a punch or other finishing-tool D', secured thereto, as shown in Figs. 10 and 11.

In Figs. 3 and 4, I have shown my improved machine as operating on large sheets having a regular curve, in which case it is desired to flange only one edge. In this case I prefer to dispense with the plungers C' C', as shown, and secure the clamping-head to only one of the plungers B' and the die to the remaining plunger B', a guide-bracket O being used for guiding the die K, as shown in Figs. 3 and 4.

The operation of the machine is as follows: Assuming that it is desired to flange a sheet of metal on all sides of a shape corresponding to that shown in Fig. 6, the proper die and clamping-head are secured to the plunger, and the anvil-block H of the desired form is secured to the girder. The metal to be operated on is placed on the anvil-block and the clamping-heads descend upon it. The platen and die K then descend upon the projecting edge and bends the same, when the clamping-head and die are again raised.

When it is desired to flange or bend a large plate which could not otherwise be operated upon except in a press of very large size, the nuts on top of pillars G G are loosened, and the pillars are then lowered down into suitable adjustable stands or rests P into either a horizontal or angular position, thus leaving one end of the press entirely free and open, and any sized plate can then be inserted and operated upon.

If it is desired to produce a flange of regular curve and of large radius, then the plate is centered or attached to the centering-pin on sliding cross-head M, which is moved in one direction by the screw F and in a direction at a right angle thereto by a similar screw E on the slide itself. The plate can then be adjusted as to distance from the die and true radius found either at one or more heats, accordingly as the flange desired is large or small, and if the desired flange takes an irregular curve the distance may be varied at will to form the curves as desired. A number of holes may be punched either in a circle or straight line by this device, either in the flange by the ram D or on the body of the plate by the vertical rams, by simply removing the forming-dies and attaching a punch or punches to the plungers, as shown in Figs.

10 and 11. Where only a single flange is desired or a flange on one side only, I prefer to secure the clamping-head to only one plunger B' and the die to the remaining plunger B', in which case I make use of a vertical guide O 65 for the die K, an opening Q being left in the lower portion of said guide for the passage of the plunger of ram.

While I have shown and described the die as operated on by four plungers and the clamping-head by two, I do not wish to be confined thereto, as more or less may be used for each without departing from the principle of my invention. The object of the ram D is to square up, corrugate, indent, or otherwise operate on the plates or sheets while held by any of the vertical rams.

Having described my invention, what I claim, and desire to secure by Letters Patent, is—

1. A metal-forming machine having rams provided at their ends with devices to act upon the metal and having hinged pillars arranged to engage the cross-head in which the rams are mounted, substantially as and for 85 the purpose described.

2. In a metal-forming machine, the combination, with power-actuated dies for forming the metal, of two hinged pillars adapted to assume substantially a horizontal position, an adjustable cross-head on said pillars, and a centering-pin adjustable on said cross-head, substantially as and for the purposes described.

3. The combination, in a metal-forming machine, of the movable and stationary dies, an adjustable cross-head carrying an adjustable centering-pin, and arms pivoted at one end to said centering-pin and adapted to be connected at their other ends with metal to be 100 operated on, whereby said metal may be moved about a given center, substantially as and for the purposes described.

4. In a metal-forming machine, the combination, with the frame composed of upper 105 and lower girders rigidly connected together at one end, of pillars hinged to the opposite end of the lower girder and adapted to engage open slots in the upper girder, and clamping-nuts on said pillars, substantially as and for 110 the purposes described.

In testimony that I claim the foregoing improvement in punching and flanging machines as above described I have hereunto set my hand this 7th day of June, 1889.

ERNEST W. NAYLOR.
